UNITED STATES PATENT OFFICE.

WILLIAM E. HIGHFIELD, OF PHILADELPHIA, PENNSYLVANIA.

WHIP-SOCKET..

SPECIFICATION forming part of Letters Patent No. 391,611, dated October 23, 1883.

Application filed August 3, 1883. Serial No. 281,865. (No model.)

To all whom it may concern:

Be it known that I, WILLIAM E. HIGHFIELD, a citizen of the United States, and a resident of Philadelphia, Pennsylvania, have ⁵ invented certain Improvements in Whip-Sockets, of which the following is a specification.

My invention relates to that class of whip-sockets which are provided with retainers for ¹⁰ engaging with the whip and preventing the withdrawal of the same, one object of my invention being to provide a ready means of retracting the retainers, so as to permit the withdrawal of the whip, and a further object being ¹⁵ to simplify and cheapen the construction of the parts. These objects I attain in the manner hereinafter set forth, reference being had to the accompanying drawings, in which—

Figure 1 is a longitudinal section of a whip-socket, showing the retainers in position for ²⁰ engaging with the whip, the latter being shown by dotted lines. Fig. 2 is a similar view showing the retainers retracted. Fig. 3 is a transverse section on the line 1 2, Fig. 1. Fig. 4 is ²⁵ a transverse section on the line 3 4, Fig. 2. Fig. 5 is a perspective view of one of the retainers detached from the socket, and Fig. 6 is a perspective view of the device for retracting ³⁰ the retainers.

³⁰ A represents the casing of the socket, which, in the present instance, is in the form of a cylindrical tube having at the top a bead or flange, *a*, carrying the usual notched ring, *b*, of rubber or other flexible material.

³⁵ Within the tube A are opposite spring-arms, B, secured to the tube at their upper ends and having segmental portions *d*, as shown in Fig. 5, which serve to engage with the rib or flange *x* upon the stock of the whip, as shown by dotted lines in Fig. 1, and thus prevent the ⁴⁰ removal of the whip from the socket until the arms are retracted, so as to free said rib from the control of the same. This retraction of the spring-arms is effected by means of cams ⁴⁵ D, carried by a cap, F, which is confined vertically to, but is free to turn on, a ring, *g*, secured to the lower end of the tube A. When these cams are in the position shown in Figs. 1 and 3, the downwardly-projecting portions ⁵⁰ *f* of the spring-arms B are free from control of the cams, and hence the portions *d* of the arms are at liberty to approach each other and confine the whip; but by turning the cap F and

its cams to the position shown in Figs. 2 and ⁵⁵ 3 said cams act upon the lower projecting ends, *f*, of the arms and force the same apart to such an extent as to free the rib *x* on the whip-stock from the control of the portions *d* of the arm, thus permitting the withdrawal of ⁶⁰ the whip from the socket.

The cap F contains, by preference, a spring cup, G, which engages with the lower end of the whip-stock and serves to properly center the same and to maintain its rib *x* in contact with the portions *d* of the retaining-arms, so ⁶⁵ as to prevent rattling.

Each of the spring-arms is preferably struck up from one piece of metal, as shown in Fig. 5, the lower projecting ends, *f*, of the arms being offset in respect to the portions *d* of the same, so as not to interfere with the engagement of said portions *d* with the rib *x* of the whip-stock, and the tube A of the socket is recessed on each side, as shown at *i* in Figs. 3 and 4, for the reception of the portions *f* of the spring-arms when the latter are ⁷⁰ retracted. ⁷⁵

Having thus described my invention, I claim and desire to secure by Letters Patent—

1. The combination, in a whip-socket, of the ⁸⁰ outer tube or casing, the internal spring-arms engaging with the whip-stock, and movable cams for acting upon said arms to retract the same, all substantially as specified.

2. The combination of the outer casing, the ⁸⁵ internal spring-arms engaging with the whip-stock, and the cap having cams for acting on said arms, and a spring-cup for receiving the end of the whip-stock, all substantially as specified.

3. The combination of the outer casing, the ⁹⁰ movable cams within the same, and the spring-retaining arms, each consisting of a single piece of metal with segmental portions for engaging with the whip-stock, and end portions laterally offset in respect to said segmental ⁹⁵ portions and projecting into the path of the cams, all substantially as specified.

In testimony whereof I have signed my name to this specification in the presence of two ¹⁰⁰ subscribing witnesses.

WILLIAM E. HIGHFIELD.
